UNITED STATES PATENT OFFICE.

RALPH D. NYE, OF CANTON, OHIO.

ELECTRIC FURNACE.

1,370,989.

Specification of Letters Patent. Patented Mar. 8, 1921.

Application filed July 9, 1920. Serial No. 394,913.

To all whom it may concern:

Be it known that I, RALPH D. NYE, a citizen of the United States, residing at Canton, in the county of Stark and State of Ohio, 5 have invented certain new and useful Improvements in Electric Furnaces, of which the following is a specification.

This invention relates to electric furnaces of the Heroult type which are mounted for 10 rocking or swinging movement to pour the charge, and more particularly to means for disconnecting the current conductor leading from the transformer to the furnace when the furnace is tilted.

15 It has heretofore been the practice to connect swinging or rocking furnaces with the transformer by means of a flexible cable conductor and the loop of this cable is sometimes necessarily required to be very long 20 which causes an exceedingly high loss of voltage from resistance and reactance, and also induction causes adjacent metallic parts of the apparatus to be unduly heated by induced currents, materially reducing the 25 amount of power reaching the furnace from a given transformer capacity.

The objects of the present invention are 30 to provide means for disconnecting the current conductors leading from the transformers to the electric furnace; to provide a flexible link between the transformer and furnace electrodes comprising cable conductors and a series of interengaging laminated plates and to provide positive means 35 for normally clamping the laminated plates together.

The above objects together with other ancillary objects are attained by providing in combination with a transformer and a 40 rocking or swinging furnace located adjacent thereto and arranged to be tilted in order to pour the charge, a cable conductor connected to the electrodes of said furnace and supported by a frame movable with the 45 furnace, conducting bus-bars leading from the transformer, and a detachable connection between the cable conductors and the transformer bus-bars such connection being a series of interengaging laminated 50 plates; and in view of the extremely high capacity of currents required for an electric furnace it is sometimes desirable to clamp the laminations together by some positive means such as the clamping means illustrated in the accompanying drawings.

The invention thus set forth in general

terms is illustrated in the accompanying drawings forming part hereof, in which—

Figure 1 is a side elevation of a rocking furnace and transformer showing the improved connection embodying the invention, parts being shown in section for purpose of illustration;

Fig. 2, an enlarged elevation of portions of the furnace and transformer showing the improved connection;

Fig. 3, a section on the line 3—3, Fig. 2; and

Fig. 4, a section on the line 4—4, Fig. 2.

Similar numerals refer to similar parts throughout the drawings.

The furnace 1, is of the rocking or swinging type and is provided upon its under surface with the toothed segment 2 engaging the rack bar 3 which is mounted upon 75 a suitable base or support 4.

For the purpose of rocking the furnace upon the rack bar 3 for pouring the charge from the spout 5, an operating mechanism is provided comprising the large gear 6, a 80 pitman rod 7 connected to the wrist pin 8 upon said gear and to a pivotal connection 9 at the rear extremity of the toothed segment 2, a pinion 10 meshing with said gear and being operatively connected in any suitable and well known manner (not shown) to the motor 11; by means of which the gear 6 is rotated to rock the furnace upon the rack bar 3 through the medium of the pitman rod 7.

An upright frame 12 is provided upon the rear side of the furnace and slidably mounted thereon is the electrode frame 13 which is adapted to be adjusted vertically upon said upright frame, and carries the 95 electrodes 14 which extend into the furnace. The electrode frame is provided with pulleys 15, cables 16 being connected to the upper end of the upright frame 12 and passing beneath said pulleys and thence upwardly over pulleys 17 which are mounted upon brackets 18 supported upon the upright frame 12, the cable 16 then passing downwardly over a suitable drum 19 which is operatively connected in any suitable and 105 well known manner with the shaft of the motor 20 by means of which the electrode frame 13 may thus be raised and lowered upon the upright frame 12.

Suitable conductors 21 are supported upon 110 the conductor frame 13 and connected to the electrodes 14, said conductors being con-

nected at their rear extremities to the flexible conductor cables 22 the rear extremities of which are supported from the frame 13 by means of hangers 23, a plurality of laminated plates 24 being fixedly connected to the rear extremities of said cable conductors.

The transformer 26 is provided with a frame 27 extending toward the furnace and carrying the transformer bus-bars 28, said bus-bars comprising a plurality of laminated plates 29, the outer plates being provided with upwardly and outwardly flared trough like flanges 30 arranged to guide the conductor plates 24 into position when a connection is made between the cable conductor plates 24 and the bus-bar plates.

In view of the extremely high current required for electric furnaces it is desirable, if not necessary, to clamp the laminated plates together by some positive means and for this purpose the levers 31 are pivoted intermediate their extremities as shown in Fig. 2, to the cross frame 33, the upper extremities of said levers having connected thereto the clamping jaws 34 which engage the opposite sides of the bus-bar plates at the point where the connection is made.

A screw threaded shaft 35 is pivotally connected at 36 to the lower extremity of one of the levers 31 and engages the nut 37 carried upon the lower extremity of the other lever 31, a hand wheel 38 being fixed upon said screw threaded shaft for operating said levers.

When the parts are in the normal position and the furnace is in operation the jaws 34 will be tightly clamped against the opposite faces of the transformer bus-bar thus positively clamping the laminations together.

It will be understood that the transformer will be provided upon the high tension side with the usual circuit breaker 40 for breaking and closing the circuit, and that the disconnecting means between the cable conductors and transformer bus-bars are not usually employed for breaking and closing the circuit.

When it is desired to tilt the furnace to pour a heat, the hand wheel 38 is operated to unclamp the jaws 34 and the tilting mechanism controlled by the motor 11 is operated, tilting the furnace forwardly away from the transformer and automatically disconnecting the conductor plates 24 from the bus-bar plate, the circuit being previously broken by the circuit breaker 40.

When the furnace is tilted back into the operative position the conductor plates 24 will automatically engage the laminations of the bus-bar plates, and the clamping jaws will be again operated to positively clamp the laminations together.

It is evident that the disconnecting means herein described, makes it possible to se-

cure the shortest path for the electric current from the transformer to the furnace electrodes; thereby reducing to a minimum the drop of voltage and loss of power.

The use of the disconnecting device also eliminates operating difficulties encountered in using long flexible loops of conductor cables, as for instance a breakage of the cables, a short circuiting thereof, and the attendant expense of upkeep, together with the loss of production due to delays in operation caused by these troubles.

I claim:—

1. In combination with a transformer and a tilting furnace, a stationary current conductor leading from the transformer, and a current conductor mounted on and moving with the furnace, in detachable engagement with the stationary current conductor.

2. In combination with a transformer and a tilting furnace, a stationary conductor leading from the transformer, and a current conductor mounted on and moving with the furnace, adapted for automatic engagement with the stationary current conductor when the furnace is moved into normal position.

3. In combination with a transformer and a tilting furnace, a stationary current conductor leading from the transformer, and a current conductor mounted on and moving with the furnace, normally engaged with the stationary conductor, and adapted for disengagement therefrom when the furnace is tilted.

4. In combination with a transformer and a tilting furnace, a stationary current conductor leading from the transformer, and a current conductor mounted on and moving with the furnace, normally engaged with the stationary conductor, and adapted for automatic disengagement therefrom when the furnace is tilted.

5. In combination with a transformer and a tilting furnace, a bus-bar or the like leading from the transformer comprising a plurality of laminated plates and a current conductor upon the furnace comprising a plurality of laminated plates arranged to engage the plates of the bus-bar.

6. In combination with a transformer and a tilting furnace, a bus-bar or the like leading from the transformer comprising a plurality of laminated plates and a current conductor upon the furnace comprising a plurality of laminated plates arranged to engage the plates of the bus-bar, and means for disconnecting said laminated plates when the furnace is tilted.

7. In combination with a transformer and a tilting furnace, a current conductor leading from the transformer to the furnace and means for disconnecting said current conductor when the furnace is tilted, said means comprising a plurality of interengaging laminated plates.

8. In combination with a transformer and a tilting furnace, a current conductor carried by the furnace and a plurality of interengaging laminated plates carried by the current conductor and by the transformer and arranged to be disengaged when the furnace is tilted.
9. In combination with a transformer and a tilting furnace, a current conductor carried by the furnace, a plurality of interengaging laminated plates carried by the current conductor and by the transformer and arranged to be disengaged when the furnace is tilted, and means for positively clamping said laminated plates together when the furnace is in operation.
10. In combination with a transformer and a tilting furnace, a stationary current conductor leading from the transformer, and a flexible current conductor mounted on and moving with the furnace, in detachable engagement with the stationary current conductor. 20
11. In combination with a transformer and a tilting furnace, a stationary current conductor leading from the transformer, and a current conductor mounted on and moving with the furnace, in detachable clamped engagement with the stationary current conductor. 25

RALPH D. NYE.
